UNITED STATES PATENT OFFICE.

PHILIPP BOCH, OF NEW YORK, N. Y.

CAR-BRAKE.

SPECIFICATION forming part of Letters Patent No. 684,178, dated October 8, 1901.

Application filed February 20, 1901. Serial No. 48,087. (No model.)

To all whom it may concern:

Be it known that I, PHILIPP BOCH, a citizen of the United States, residing in New York, borough of Queens, in the State of New York, have invented certain new and useful Improvements in Car-Brakes, of which the following is a specification.

This invention relates to certain improvements in the car-brake for which Letters Patent of the United States were granted to me, No. 663,827, dated December 11, 1900, the improvements being designed with the view of permitting not only vertical movement of the rail brake-shoe, but also lateral motion of the rail brake-shoe, so as to permit the easy rounding of curves and to impart such a degree of flexibility to the rail brake-shoe as required by the various exigencies to which the rolling-stock is subjected.

The invention consists of a car-brake which comprises guide-plates suitably supported on the car-truck, side plates guided by said guide-plates, a brake-beam supported by said side plates, swinging arms suitably supported on the side plates, rail brake-shoes carried by the outer ends of the swinging arms, means for holding the said brake-shoes in released position, means for applying the said brake-shoes, and means connecting the pivoted arms for permitting the lateral motion of the rail brake-shoes, so as to follow the rails without injurious strains on the operative parts; and the invention consists, lastly, of certain details of construction and combinations of parts, which will be fully described hereinafter and finally claimed.

In the accompanying drawings, Figure 1 represents a side elevation, partly in section, of my improved car-brake, showing the same applied to the frame of the car-truck and in inoperative position. Fig. 2 is a horizontal section on line 2 2, Fig. 1. Fig. 3 is a like side elevation to Fig. 1, showing the brake in position applied to the wheels and rails and in which the car is supposed to be turning a curve. Fig. 4 is a horizontal section on line 4 4, Fig. 3; and Fig. 5 is a plan view of my improved brake and its operative mechanism.

Similar letters of reference indicate corresponding parts.

Referring to the drawings, A A represent a portion of the truck-frame which is equipped

with my improved brake, said frame having bracket extensions A' connected by a cross-beam B of T-shaped cross-section. On these 55 bracket extensions A' are mounted the working parts of the brake, which are supported more directly on parallel guide-plates C, that are attached to said extensions at opposite sides of the car-truck by means of clamp-bolts C' C', that fit over the extensions and are attached thereto by screw-bolts C², which rigidly bind the fixed portion of the clamps down upon said extensions. The 60 guide-plates C are preferably shaped in such 65 manner that their outer extremities are located approximately in the vertical planes of the car-wheels. The brake itself is composed of two brake-shoes, the one, D, being the rail brake-shoe, and E the wheel brake-shoe, suitably supported on the movable side plates F.

G is the brake-beam, of T-shaped cross-section, the ends of which are suitably secured to the side plates F, as shown in Figs. 1 and 3, by means of saddles F', which project from the side plates F and are fixed thereto by suitable fastening devices. The guide-plates C are provided at points preferably above and below the axles with inclined slots c' and c², respectively, said slots receiving and guiding the pins f f', projecting from the plates F. At the inner side of the brake-beam G are lugs or brackets g, to which are pivoted the lower ends of links h, the upper ends of which are secured to rods H, which 75 are guided in lugs or brackets b, secured to the inner side of the cross-beam B. The rods H are screw-threaded at their upper ends to receive the nuts h', between which and the lugs b helical lifting-springs I are confined which tend to draw the side plates F in upward direction, together with the wheel 80 brake-shoes D, which are thereby held in raised position above the rails T, as shown in Fig. 1. The slots c' c² and pins f f' direct the 85 side plates F in such manner as to permit the springs I to simultaneously draw the wheel brake-shoes E away from contact with the treads of the car-wheels W.

K K indicate actuating-levers which are 90 connected by cross-rod K', to which is pivoted the draw-rod L, which leads to a suitable point, so as to be operated by the motorman or engineer. The levers K are pivoted to

lugs b' on the cross-beam B and are also pivoted at k' to the wedge-shaped depressors M, whose upper and lower surfaces bear on anti-friction-rollers o and p, mounted in suitable bearings of the cross-beam B and brake-beam G, respectively. Integral with each of the depressors M is formed a hook M', which extends downward at right angles thereto and which constitutes a latch, the hooked lower end of which is adapted to engage with the under side of the brake-beam G, so as to positively lock the brake-shoes in raised or inoperative position until released by the action of the lever K.

15 The parts so far described correspond more or less to the operative parts of the brake construction heretofore patented by me. The new feature of this invention consists in the peculiar means by which a lateral motion is 20 imparted to the rail brake-shoes D relatively to the side plates F. For this purpose the rail brake-shoe is provided at its rear end with a downwardly-extending lug that extends sidewise of the rail-head. The rail 25 brake-shoe D is also provided with an upwardly-extending lug D', that is pivoted to an intermediate block D², which is connected by a laterally-extending arm D³ with a bracket-arm D⁴, that extends from the side plate 30 F. The block D² is provided with a curved 35 transversely-extending guide portion D⁵, guided in a recess D⁶ in the side plate F and which receives an antifriction-roller Y, applied in suitable bearings of the side plate F, as shown in Figs. 2 and 4, said guide portion being curved concentric with the pivot d and both guide portions being provided with extension-eyes d', connected by a rod D⁷, as shown in Fig. 5. By means of the guideways 40 on the auxiliary block D² the block, together with the rail brake-shoe, will be automatically shifted out of the plane of the supporting guide-plate F into either direction, according to the curvature of the track, the 45 shifting motion being imparted by contact of the downwardly-extending guide-lug with the side of the rail-head, so that thereby the brake adapts itself readily to the track without ex-

erting any strain on the operative parts of the brake.

What I claim as new is—

1. In a car-brake, the combination of guide-plates supported from the car-truck, a brake-beam suitably guided between said plates, pivoted arms suitably supported from the 55 brake-beam, rail brake-shoes mounted on the free ends of the said arms, means for connecting the said arms, and means for applying the brake, substantially as set forth.

2. In a car-brake, the combination of guide-plates supported from the car-truck, side plates guided on said guide-plates, a brake-beam supported by said side plates, arms pivoted at one end to portions of said side plates, rail brake-shoes carried by the other ends of 60 the arms, means for connecting the arms, and means acting on the brake-beam for applying the brake, substantially as set forth.

3. In a car-brake, the combination of suitably-connected side plates, means for mounting the same movably on a car-truck, arms pivoted at one end to portions of said plates, and provided with curved guide portions, antifriction-rollers mounted in the side plates and on which the side portions bear, rail 70 75 brake-shoes carried by said arms, and means for applying the brake-shoes, substantially as set forth.

4. In a car-brake, the combination of connected side plates, means for supporting the 80 same, movably from the car-truck, arms pivoted at one end to said plates, blocks carried by the free ends of said arms, rail brake-shoes pivoted to said blocks, curved guide portions also carried by the arms, antifriction-rollers 85 mounted in the side plates and on which said guide portions bear, and means for moving the side plates for applying the brake-shoes, substantially as set forth.

In testimony that I claim the foregoing as 90 my invention I have signed my name in presence of two subscribing witnesses.

PHILIPP BOCH.
